UNITED STATES PATENT OFFICE.

HENRY SCHLOETZER, OF NORTH BERGEN, NEW JERSEY.

EMBROIDERY FRAME.

Application filed April 21, 1923. Serial No. 633,719.

This invention contemplates the provision of an attachment for embroidering machines, the attachment being in the nature of a floating frame to which the material is secured, the frame being designed to support different pieces of fabrics, such as handkerchiefs or other novelties for each needle, and hold the fabrics so that any particular part of the same can be embroidered.

10 The chief object of the invention resides in providing a floating frame attachment for machines of the above mentioned character, characterized by the ease with which the fabric can be attached to or removed

15 from the frame, as the occasion may require.

The nature and advantages of the invention will be better understood when the following detailed description is read in connection with the accompanying drawings,

20 the invention residing in the construction, combination and arrangement of parts as claimed.

In the drawings forming part of this application, like numerals of reference indicate similar parts in the several views, and wherein:

Figure 1 is a plan view of the frame forming the subject matter of the invention, illustrating the manner in which the fabric

30 is attached thereto.

Figure 2 is a sectional view taken on the line 2—2 of Figure 1.

Figure 3 is a sectional view taken on the line 3—3 of Figure 1.

35 Figure 4 is an end elevation.

Figure 5 is a detail view of one of the clamping elements.

40 Figure 6 is a detail view of a pair of clamping rods showing the connection between the same.

The frame above referred to is adapted to be clamped in numbers to embroidering machines in vertical positions and each frame is made up of a plurality of verti-

45 cally disposed bars 10 which are arranged in spaced parallel relation and of channel like formation in cross section. These bars are associated with end members as shown, each member being of substantially L-shaped for-

50 mation in cross section and including spaced parallel portions 11 and 12 respectively. These portions are notched as at 13 to accommodate the adjacent ends of the bars 10 as well as the clamping rods to be herein-
55 after described. The innermost portion 12 of each end member is utilized to hold the

end members associated with the bars 10, the latter terminating at both ends to provide attaching portions 14 which are arranged in contacting engagement with the 60 said portions 12 of the end members, and secured thereto by suitable fastening elements 15. The spaced portions 11 and 12 of each end member have arranged therebetween spaced elements 16, disposed at either 65 side of the notches 13, and pivotally associated between these spacing elements are hooks 17 which are arranged to engage the clamping rods 18 to hold the latter in clamping position. As will be noted from 70 the drawings, there are two of these rods associated with each vertical bar 10, and each rod is constructed of resilient material normally curved. The adjacent ends of each pair of rods 18 are formed with eyes 75 19, so that these rods are pivotally mounted on pins 20 supported by a U-shaped member 21 designed to fit within the channel bar 10 at a point between the ends thereof. Each rod 18 is partly covered with a sleeve 80 22 of relatively soft material, such as rubber, cloth or the like, so that these rods will not injure the fabric which is clamped to the frame by means of said rods. The rods are of a length to extend slightly beyond the 85 end members of the frame being received by the notches 13 and held in extended or straightened positions by the adjacent hook like elements 17. Consequently, when the rods are thus arranged, they are placed under tension to effectively grip and hold the fabric 22 secured to the adjacent bars 10 as shown in Figure 1 of the drawings, the hook like elements 17 as above stated hold the rods in clamping position within the channel like bars 10. The hooks 17 are balanced gravity hooks, and automatically engage and disengage the spring rods.

The frame is divided into upper and lower sections by a transverse member 23 which is also of channel formation in cross section and provided with notches in its sides to receive the bars 10, so that the upper or open edges of these bars lie flush with the open side of the member 23. This member 100 23 as above set forth is of substantially channel formation in cross section, and each parallel side terminates to provide a substantially L-shaped flange 24. As a matter of fact, the transverse member is made up of a plurality of spaced U-shaped portions 23' connected by the L-shaped flanges 24. The

bottom of each U-shaped portion is cut-away along the opposite sides of the longitudinal center, and the material thus cutaway in each instance is bent to provide parallel ears 26 between which the bars 10 are clamped, the pin 20 upon which the clamping rods are mounted, being utilized as means for clamping the ears to the bars 10 as shown in Figure 5 of the drawings.

Arranged within the transverse member just described is a plurality of pivoted spring pressed clamping elements 28, each of which is of L-shaped formation. These clamps are arranged in pairs between the vertical bars 10, and are pivoted between spaced apertured lugs 29 which are struck from the bottom of the U-shaped portions 23' of the transverse member as illustrated in Figure 5. It will be further noted that the clamping members 28 of each bar are reversely disposed, so that one branch of each clamping member cooperates with the adjacent L-shaped flange 24 of the transverse member for the purpose of clamping a portion of the material or fabric to this member. This particular branch of each clamp is indicated at 28', and while the clamping portion is constructed of metal or other suitable material, it is covered by rubber or other relatively soft material, so that the fabric will not be injured by being clamped between the L-shaped flange and said clamping member. Positioned between each pair of clamping members is a plate 30, which plates also lie between the adjacent U-shaped portions of the transverse member. The plates 30 span the spaces between the U-shaped members 23', and form needle guards to prevent the needles of the embroidery machines from getting caught in that portion of the fabric held by the branches 28' of the clamping members 28, as it will be obvious that a portion of the fabric will extend inwardly beyond the L-shaped flange 24 and be disposed upon the outer surface of the plates 30. In other words, these plates 30 protect the fabric from the needles of the embroidery machines when the frames are raised or lowered in the machines for moving the needles of the machines from one section of the frame to the other when it is desired to embroider the material in the opposite sections as will be readily apparent. Therefore, it will be seen that the space between the U-shaped members 23' and below the plates 30 will provide needle passages 30' and yet the portions of the fabric extending into the U-shaped members will be amply protected. It is by means of these passages that the needle passes from one fabric holder to the other thereby making the double fabric holder possible. It is quite obvious from the construction illustrated and described that handkerchiefs, novelties or other fabric can be easily and

quickly clamped upon or removed from the floating frame, and arranged in any manner so that any particular part of the fabric can be embroidered, there being in reality two fabric holders for each needle.

While I have disclosed a single frame in Figure 1 of the drawings, a number of frames arranged in sections from six to seven and one-half feet long to provide a set may be secured to an embroidery machine, as previously set forth, and held thereon in a vertical position through the medium of lugs on said machine. In practice, while one set of frames is arranged on the embroidery machine, with material therein being embroidered, another set of frames are being filled with material to replace the set in the machine, when the work on the material in the last mentioned set is finished. Of course, a single frame as shown can be clamped to an embroidery machine.

From the above, it will be seen that the frames are to be vertically disposed with respect to the embroidery machines, and the needles of the machines operate on the material in one section, preferably the upper section of the frame, and then the frame is moved upwardly so that the needles can operate on the fabric in the lower portion of the frame. The fabric is shown in the lower portion of the frame in Figure 1 of the drawings. In moving the frame vertically on the embroidery machines, it will be obvious that the needles will remain stationary, and the needle passages 30' which are disposed between the members 23' allow the vertical movement of the frame without fear of the needles catching in the fabric during the process of moving the frame.

While it is believed that from the foregoing description, the nature and advantages of the invention will be readily apparent, I desire to have it understood that I do not limit myself to what is herein shown and described and that such changes may be resorted to when desired as fall within the scope of what is claimed.

Having thus described the invention, I claim:

1. A fabric supporting frame of the character described including a plurality of spaced vertical bars, each bar being of channel formation, a transverse member connecting all of said bars centrally thereof, normally curved resilient rods arranged in pairs in each bar, and having their adjacent ends pivotally mounted on the bar, balanced gravity hooks for holding said rods within said bars and parallel therewith for clamping a portion of the fabric to the bars, and substantially L-shaped clamping members carried by the transverse member for clamping the adjacent portions of said fabric thereto.

2. A fabric supporting frame of the char-

acter described including a plurality of spaced vertical bars of channel formation, end members connecting said bars, a transverse member arranged centrally of the frame and associated with all of said bars, said transverse member being of channel formation in cross section, and made up of a plurality of U-shaped members, substantially L-shaped in cross section flanges connecting the U-shaped members and cooperating clamping means arranged in said bars and said U-shaped members for clamping the adjacent portions of the fabrics to the frame for the purpose specified.

3. A fabric supporting frame of the character described including spaced vertical bars, said bars being of channel like formation in cross section, a transverse channel like member connecting said bars centrally, clamping elements cooperating with the vertical bars and substantially co-extensive in length therewith, and pivoted clamping elements of L-shaped formation arranged in reversed pairs to cooperate with the transverse member for clamping the fabric thereto.

In testimony whereof I affix my signature.

HENRY SCHLOETZER.
